MICHAEL I. PUPIN, OF NORFOLK, CONNECTICUT, AND EDWIN H. ARMSTRONG, OF YONKERS, NEW YORK.

MULTIPLE ANTENNA FOR ELECTRICAL WAVE TRANSMISSION.

1,388,441.

Specification of Letters Patent. Patented Aug. 23, 1921.

Application filed October 1, 1915, Serial No. 53,494. Renewed January 14, 1921. Serial No. 437,358.

To all whom it may concern:

Be it known that we, MICHAEL I. PUPIN, a citizen of the United States, residing in Norfolk, county of Litchfield, State of Connecticut, and EDWIN H. ARMSTRONG, a citizen of the United States, residing in Yonkers, county of Westchester, State of New York, have invented certain new and useful Improvements in Multiple Antennæ for Electrical Wave Transmission; and we do hereby declare the following to be a full, clear, and exact description of the invention, such as will enable others skilled in the art to which it appertains to make and use the same.

The invention relates to the screening of a high resistance wireless receiving antenna against the disturbing effects of electrical impulses of short duration by connecting it to another antenna of low resistance and low inductance.

Figure 1 is a representation of a construction which embodies this invention and Fig. 2 shows a modification.

4, 3, 5 is a linear low resistance vertical antenna in which there is no inductance except the uniformly distributed inductance naturally associated with it. Let its height be 500 feet. Its natural period of oscillation will be about 2×10^{-6} seconds, and its damping very high, since, as is well known, an antenna of this construction is a very good radiator. The high resistance antenna 3, 1, 6 is connected at 3 to the low resistance antenna. This high resistance antenna is the receiving antenna and it is supposed to be tuned to some frequency which is within the interval of frequencies now employed in wireless transmissions, that is, between twenty and one hundred thousand periods per second. On this account it carries large amounts of lumped inductance, as indicated at 7. This large inductance load in addition to the high resistance load, which the high resistance antenna carries, makes its coupling to the low resistance antenna very loose, in spite of the fact that the linear parts of the two antennæ are as closely coupled to each other as practicable. When an electrical pulse of short duration strikes the two antennæ the low resistance antenna will absorb

the electromagnetic energy conveyed by the pulse. The sudden rise of the magnetic field established around it by the action of the pulse will prevent the pulse from communicating any appreciable amount of energy to the high resistance antenna. A simple mathematical consideration, which is within reach of those skilled in the art, will show the correctness of this statement. The electromagnetic energy established by the pulse in the field of the low resistance antenna is dissipated by electrical oscillations in it which are of the natural frequency of the low resistance antenna. This frequency is very high and substantially the same as if the high resistance antenna were not present at all, since the coupling between the two is very loose. These high frequency oscillations produce in the high resistance antenna very little or no effect not only on account of the fact that the high resistance antenna is not tuned to these high frequencies, but also on account of the fact that the high frequency oscillation on the low resistance antenna is excessively damped by the well known radiating power of such antennæ.

For simple harmonic waves of the ordinary frequencies now employed in wireless transmissions, this low resistance antenna is practically impenetrable, so that its connection with the tuned high resistance antenna will not appreciably affect the responsiveness of this antenna for waves to which it is tuned.

A very simple form of coupling of the two antennæ has been described but it is obvious that many variations may be introduced without departing from the essential principles of this invention. For instance, several low resistance antennæ running parallel to the high resistance antenna may be employed with considerable advantage. Such an arrangement is shown in Fig. 2 in which a number of low resistance antennæ 5 are disposed about the high resistance antenna 6 and connected to the latter and to each other. It will be understood, however, that the low resistance antennæ may be of any number, and may be arranged in any convenient manner with respect to the high resistance antenna.

What we claim is:

A wireless receiving antenna of such high resistance as effectively to screen the system against disturbing electromagnetic waves impressed upon the conductor, in inductive relation with a low resistance and low inductance antenna which serves as a screen

protecting the high resistance antenna against electromagnetic pulses of short duration.

In testimony whereof we affix our signatures.

MICHAEL I. PUPIN.
EDWIN H. ARMSTRONG.
